GAME BOARD

Roy M. Neece, Fort Worth, Tex., assignor to
Tempo-Toy, Fort Worth, Tex.

Filed Nov. 5, 1971, Ser. No. 196,261

Term of patent 7 years

Int. Cl. D21—01

U.S. Cl. D34—5 SS

Fig. 1

Fig. 2

FIG. 1 is a perspective view showing the front and two sides of a game board in accordance with my new design; and

FIG. 2 is a perspective view showing the back and other two sides thereof.

I claim:

The ornamental design for a game board, as shown.
